CORPORATION OF NEW YORK.

TURNSTILE.

1,382,575.

Specification of Letters Patent. Patented June 21, 1921.

Original application filed December 26, 1918, Serial No. 268,275, now Patent No. 1,339,076, dated May 4, 1920. Divided and this application filed April 7, 1920. Serial No. 371,813.

To all whom it may concern:

Be it known that we, CONRAD D. TRUBENBACH and DIEDRICH BALDWIN SANNEMAN, citizens of the United States, and residents, 5 respectively, of Mount Vernon, in the county of Westchester and State of New York, and of the borough of Brooklyn, city, county, and State of New York, have invented a new and useful Improvement in 10 Turnstiles, of which the following is a specification.

This invention relates to turnstiles, and particularly to turnstiles that are adapted to be moved from place to place.

15 The object of the invention is to provide a turnstile that can be moved from one operative position to a second operative position.

Another object is to provide a turnstile 20 that can be shifted from one spot to another so that only one turnstile need be used instead of two; as in a double-end or Y car for instance.

With these objects in view the invention 25 consists in certain novel features of construction, and in certain parts and combinations hereinafter to be described, and then more particularly pointed out in the claims.

In the accompanying drawings:

30 Figure 1 is a plan view of the forward part of a double end car showing a turnstile embodying the invention in position in full lines, and also showing the position in dotted lines of the same turnstile when the car 35 is going in the opposite direction; the line M—N being the transverse center line of the car.

Fig. 2 is a transverse cross section of the 40 said car on the line A—B of Fig. 1, looking toward the front end of the car.

Fig. 3 is a front elevation of the turnstile and its appurtenances along the line C—D.

Referring now to these drawings, 1 represents the car, 2 the forward entrance there- 45 to, 3 the motorman's seat, 4 the controller, 5 the drop-handle brake, 6 the airbrake, 7 the railings, 8 the passenger seats, and 9 the exit; all of which are positioned as usual in the standard double-end car.

50 When adapted to be used in a car, the invention is constructed and mounted substantially and preferably as follows: Along the transverse center line M—N of the car, and on one side of the longitudinal center line C—D of the same, the turnstile 10 is re-

leasably mounted. The base 11 has wheels or rollers 12 attached thereto, each wheel having a flange in the center thereof and rolling in a grooved track 13 the said groove thereof registering with the flange of the 60 said wheels. This track extends for about two-thirds the distance across the platform floor, or roof of the car from side to side thereof, and if laid on the platform or floor of the car is flush with the same. 65

When the turnstile arrives at the end of its track, on one or the other of the sides of the car, bolts or fasteners 14 on the said base fall by gravity into the holes 15 provided therefor, and adjacent to each end of 70 the said track, and may be fastened therein in any convenient manner to clamp the turnstile in place.

A change-board, counter, or shelf 16 behind which the conductor stands, is mounted 75 above the turnstile and is releasably attached thereto, and runs on a separate track 17 grooved similarly to the track 13, the frame or legs 18 from the said change-board projecting downwardly and ending in rollers 19 having a center flange similar to that of the said wheels or rollers 12. 80

A hand or foot lever 20 projects from the turnstile as usual, and from the outer end of the same a cord 21 runs over a pulley 22 85 attached to the top of the said changeboard. The said rope then runs over the top of the changeboard as at 23, then under a second pulley and ends in handle 24.

A second handle 25 is attached adjacent 90 to the said first mentioned pulley 22, so that the operator can operate the said lever 20 if desired from either side of the change board.

A stool 26 with legs or stand 27 and floor 95 flange 28 fitting in a hole 29 in the floor of the car may be used by the operator if desired.

Vertical posts, poles or standards 30 rise from the floor of the car to the roof thereof, and are rigidly fastened to the top and the bottom of the same. Over these posts, by means of sleeves 31, slides the horizontal bar 32 in line with the longitudinal center line C—D of the car, the bar being prevented 100 from dropping below the required height by the stops 33 which stops are provided with rubber cushions 34. When raised to its highest point as at 35, spring catches 36 in the said poles 30 prevent the bar from fall- 110

ing, and similar locks or catches hold the bar in its lower position.

Permanent partitions 136 rise from the floor to the ceiling of the car having open 5 or wire-glazed panels 37 therein; and at the outer sides of two of these partitions are located slideable doors or partitions 38, sliding on countersunk tracks 39 which run across the floor to the said vertical posts. Locks 10 40 hold the doors 38 to one or the other of the said posts. The upper panels of these slideable doors register with the panels in the permanent partitions so that sight and ventilation are not interfered with to any 15 appreciable extent.

The operation of the invention is essentially and preferably as follows: The car is traveling in the direction of the arrow 44, and therefore the passengers will board the 20 car at the forward door or entrance 2, and will either decide to remain in the forward end of the car in the seats 8 and pay their fares when arriving at or near their destination, or they will pass through the turn- 25 stile into the rear part of the car where the seats may be unoccupied.

As one by one they pass into the narrow passageway 42 they pay their fares to the conductor seated or standing behind the 30 change-board 16. The passengers then walk one by one toward the turnstile and when the conductor pulls the cord 21, which releases the mechanism of the turnstile, the passenger pushes his way through the same 35 and may immediately go through the passageway 43 and out through the exit 9. Or he may pass through and beyond the passageway 43 and occupy the seats in the rear end of the car, Fig. 1 showing but half of the 40 car to the right of the transverse line M—N.

At the same time that the passenger passes through the turnstile, the latter automatically registers his presence in the car and there is no way for the conductor to dispute 45 this or derive any benefit from the fare of the passenger.

When the end of the route has been reached by the car, the conductor unfastens the bolts in the base of the turnstile, un- 50 locks the forward partition from the vertical post, lifts up the horizontal bar until the spring catches hold the same, and pulls over the turnstile and the change-board along their respective tracks to the dotted 55 positions shown in Fig. 1. As soon as the turnstile and change-board arrive at the end of their respective tracks the bolts in the base of the turnstile and the legs of the change-board automatically slip into their 60 respective holes in the floor and are fastened therein. The conductor then slides the forward movable partition back into its inoperative position. The horizontal bar is then brought down to its lower position and 65 the opposite or rear movable partition is

drawn toward the rear center pole and locked thereto. After the conductor's seat has been placed in position, the car starts on its homeward journey and the conductor is ready to receive the fares of the passengers 70 who are now coming toward the turnstile from the reverse direction.

The invention is not limited in its use to double-end street railway cars only, but may be used in any other kind or type of car; 75 or on any other kind of vehicle; and may be used on a non-moving platform if desired. Nor is the invention limited to any particular kind or type of turnstile; and the base mentioned may be separate from the turn- 80 stile or the same can be cast integral with the turnstile or be done away with entirely.

It must be understood that various changes may be made in the form, proportion, size and detail of the several structures shown, as 85 well as in the number and position of certain elements used, without departing from the spirit of the invention.

This application is a division of our previous application filed December 26, 1918, 90 and serially numbered 268,275, now Patent 1,339,076, dated May 4, 1920.

We claim:—

1. The combination with a turnstile, of a platform, a track laid upon said platform, 95 wheels on the turnstile registering with the said track and permitting the turnstile to be moved from its normal operative position to a second operative position.

2. The combination with a turnstile, of a platform, a track laid upon said platform, 100 wheels on the turnstile registering with the said track and permitting the turnstile to be moved from its normal operative position to a second operative position, and means 105 for clamping the turnstile in both its said operative positions.

3. The combination with a turnstile, of a movable base for holding the turnstile, and permitting the turnstile to be moved from 110 its normal operative position to a second operative position.

4. The combination with a turnstile, of a movable base for holding the turnstile, and permitting the turnstile to be moved 115 from its normal operative position to a second operative position, and means for clamping the turnstile in both its said operative positions.

5. The combination with a turnstile, of 120 a car, a change board, and tracks over which the turnstile and said change board travel from one part of the car to the other.

6. The combination with a turnstile, of 125 a car, a change-board, and tracks over which the turnstile and said change-board travel from one side of the car to the other.

7. The combination with a turnstile, of 130 a car, a change-board mounted adjacent to the turnstile, and tracks over which the

turnstile and the said change-board travel from one part of the car to the other.

8. The combination with a turnstile, of a car, a change-board mounted above the 5 turnstile, and tracks over which the turnstile and the said change-board travel from one part of the car to the other.

9. The combination with a turnstile, of a car, a change-board and tracks mounted 10 adjacent to the center of the said car and running transversely across the same over which the turnstile and the said change-board travel from one part of the said car to the other.

15 10. The combination with a turnstile, of a car, a change-board, tracks over which the turnstile and said change-board travel from one part of the car to the other, and means for operating the turnstile from the said 20 change-board.

11. The combination with a turnstile, of a car, a change-board, tracks over which the turnstile and said change-board travel from one part of the car to the other, and 25 means for operating the turnstile from the said change-board from either side thereof.

12. The combination with a turnstile, of a car, a change-board straddling tracks over which the same and the turnstile travel from 30 one part of the car to the other.

13. The combination with a turnstile, of a car, a change-board, tracks over which the turnstile and said change-board travel from one part of the said car to the other, 35 and means for operating the turnstile from the said change-board from either side thereof comprising a cord attached to the operating mechanism of the turnstile and running up to the said change-board and 40 across the same.

14. The combination with a turnstile, of a car, a change-board, tracks over which the turnstile and the said change-board travel

from one part of the car to the other, means 45 for operating the turnstile from the said change-board from either side thereof comprising a cord attached to the operating mechanism of the turnstile and running up to the said change-board and across same, and handles attached to the said cord one 50 on each side of the center line of the said change-board.

15. The combination with a turnstile, of a car, a track in the said car over which the turnstile travels from one side of the said 55 car to the other, means for clamping the turnstile to the floor of the car adjacent to either end of the said track, a change-board mounted adjacent to the turnstile, and a second track on which the said change-board 60 travels from one side of the car to the other.

16. The combination with a turnstile, of a car, a track on the floor of the said car over which the turnstile travels from one side of the said car to the other, means for 65 clamping the turnstile to the floor of the car adjacent to either end of the said track, a change-board mounted adjacent to the turnstile, a second track on which the said change-board travels from one side of the 70 car to the other, and a connection between the turnstile and the said change-board.

17. The combination with a turnstile, of a car, a track on the floor of the said car over which the turnstile travels from one side 75 of the said car to the other, means for clamping the turnstile to the floor of the car adjacent to either end of the said track, a change-board mounted adjacent to the turnstile, a second track on which the said 80 change-board travels from one side of the car to the other, a connection between the turnstile and the said change-board, and means for operating the turnstile.

CONRAD D. TRUBENBACH.
